UNITED STATES PATENT OFFICE.

WILLIAM WERTS, OF CAMDEN, NEW JERSEY.

COVER-FASTENING FOR FRUIT-JARS.

SPECIFICATION forming part of Letters Patent No. 356,565, dated January 25, 1887.

Application filed April 9, 1886. Serial No. 198,363. (Model.) Patented in Canada June 23, 1886, No. 24,382.

To all whom it may concern:

Be it known that I, WILLIAM WERTS, a citizen of the United States, residing at Camden, in the county of Camden and State of New Jersey, have invented a new and useful Improvement in Cover-Fastenings for Fruit-Jars, of which the following is a specification.

My invention relates to an improvement in cover-fastenings for fruit-jars; and it consists in the peculiar construction and combination of devices, that will be more fully set forth hereinafter, and particularly pointed out in the claim.

In the drawings, Figure 1 is a perspective view of a cover-fastener embodying my improvements. Fig. 2 is a vertical sectional view of the same. Fig. 3 is a similar view taken at right angles to Fig. 2.

A represents the upper portion of a fruit-jar, which is provided with a shoulder, B, at its upper end, and a neck, C, below the shoulder, of slightly reduced diameter.

D represents a collar which encircles the reduced neck of the jar, and is provided in opposite sides with openings d. E represents a bail, which is formed from a single piece of wire, and is bent substantially in the shape of an inverted letter U, whereby the bail is provided with the horizontal connecting-yoke e and the vertical depending arms e'. The lower ends of the arms are bent inwardly at right angles, thereby forming engaging-points e'', which enter the openings d of the collar and pivot the bail thereto. The upper end of the jar is provided with the usual vertical flange, F, and the sealing rubber ring G.

H represents a cap or cover, which is formed of any suitable preferred material, and is provided with a depending flange, h, which fits over the flange of the fruit-jar and bears on the upper side of the sealing-ring. On the upper side of the cap or cover are vertical aligned bosses h', the upper sides of which are hollowed or notched, as at h''. The collar D is usually constructed of metal. The cap or cover H is usually constructed of metal or glass. The bosses may be formed separately from the cover and then inserted therein, as shown in Fig. 3, or may be formed integrally with the cover. When the bosses are formed integrally

with the cover, they are, of course, made of the same material as the latter.

I represents the keeper, which is made of a single piece of wire bent to form the outer arm, K, the eyes L, and the transverse arm M, which depends from the eyes and is arranged at right angles to the arm K. The eyes L are located at an intermediate point of the keeper, between the arm K and the bearing-arm M. When the keeper is secured in position to lock the cover, the arm K extends downward from the arm e of the bail in an inclined line and rests at its outer free end upon the top of the cover. The arm K is curved on its sides to an intermediate point, where it is shaped to provide an operating knob or projection for convenience in manipulating the fastening.

The operation of my invention is as follows: The bail E, before being attached to the collar of the jar, is first passed through the eyes of the keeper, and thereby pivoted thereto. The points e' of the bail are then caused to engage the opening d of the collar, thus pivoting the bail to the jar, and adapting the same and also the keeper to be swung to one side of the jar, in the position indicated in dotted lines in Fig. 2, and thus prevent the said keeper and bail from becoming lost or detached accidentally from the jar. When the jar is filled with fruit, the sealing-ring is applied to the upper end thereof and the cover or cap fitted thereon and arranged with its bosses in a line with the bail. The latter is then swung upwardly over the top of the jar, and the keeper is grasped by means of the arm K, and the arm or bail M thereof is caused to engage the notches in the upper ends of the bosses. By pressing the arm K downwardly to the position shown in Fig. 1, the cap is compressed tightly on the upper side of the sealing-ring, and thereby secured firmly to the jar, making a perfectly airtight joint therewith. The resilience of the sealing-ring and also of the bail E causes the arm K of the keeper to be forced firmly down on the upper side of the cover or cap, and thus prevents it from being accidentally raised and releasing its pressure on the cap or cover.

I am aware that a cover-fastening device comprising a pivoted bail and a keeper pivoted on the bail and made in the form of a

cam to act against the cover of the jar is not new. My device differs from this in the fact that I employ a transverse arm to bear against the cover throughout its length, and not at a particular spot, such as a cam would do. Again, the arrangement of the eyes L at the point where the two arms join causes the arm M to extend vertically from the pivot-point, so that considerably more pressure can be applied than if the action were in a curved line. The bosses effectually hold the arm M from slipping when the arm K is being worked. The shoulder, B, formed on the vessel is of greater diameter than the normal diameter of the vessel. The collar fits around the normal diameter of the jar or vessel below and against the shoulder, so as to come flush with the latter. By providing openings in the collar to receive the pivots of the cover-fastening means I avoid the objectionable methods of securing a wire ring around the jar and other means resorted to for this purpose.

I am aware of patent to Briggs, No. 314,099, which shows a jar-fastener comprising a pivoted bail, and a lever pivoted at its ends to hold the lever down. My device differs from this in that I do not require a latch to hold down the keeper.

I am also aware that in patent to Bate, No. 167,633, is shown a bottle-stopper having a pivoted bail, in the ends of which is pivoted a rock-shaft carrying a cam-lever, the short arm of which bears on the stopper, and the long arm serves as a handle. In this construction the rock-shaft, with the cam-lever, must be made out of cast metal, and cannot be shaped from wire so as to be sold as cheaply as mine. Again, Bate is required to use guides for the cam-lever, which in my construction are not necessary.

I am also aware of the Stevens bottle-stopper patent, No. 205,105, in which is shown a pivoted bail connecting with the bottle, and a keeper made from a piece of wire pivoted on the bail, connected to the stopper, and having an operating-handle. In my device the keeper is not connected to the cap or stopper, and, indeed, it is to avoid the objectionable features of the fastener which connects with the cover or stopper that I provide a transverse arm to bear on the cover. This transverse arm is not shown in the Stevens patent.

Also, the Lewin patent, No. 206,254, illustrates a bottle or jar cover employing a pivoted bail carrying a cam-lever to act upon the center of the cover. In this patent the top of the jar-cover is recessed to receive the cam, so as to hold the latter from moving laterally. By this construction the pressure on the cover is only applied in the center, while in my fastener the pressure is entirely across the cover, and the bosses are provided not to hold the parts from lateral movement, as in the Lewin patent, but to prevent the arm M from moving when the hand-lever K is being operated. The patent to Moody, No. 324,036, shows a jar-fastener comprising a double cam made from wire and pivoted on a bail connected to the sides of the vessel. This patent does not employ notched bosses, and has no arm, like M, to bear upon the cover from one side to the other. This curved portion of the double cam in this patent does not bear upon the cover. In my device both the arm M and arm K bear upon the cover, while in the Moody patent only the part which corresponds to arm K rests upon the cover. I therefore disclaim each of the several constructions set forth.

Having thus described my invention, I claim—

The cover or cap having the aligned notched bosses h' on its upper or outer face at opposite sides, in combination with the bail E, substantially U-shaped in form and pivoted at its ends to the sides of the vessel, and the keeper made of a single piece of wire bent to provide the transverse arm M, extending entirely across the cap or cover and seated on the bosses, the eyes L at the ends of the arm, receiving the bail, and the arm K, bent downward from the eyes and having its main portion arranged in a horizontal plane, so as to rest flat on the cover, the arms K M being arranged at right angles to each other, the arm M extending in a vertical line, and the eyes L coming at the junction of the two arms, substantially as described.

In testimony that I claim the foregoing as my own I have hereto affixed my signature in presence of two witnesses.

WILLIAM WERTS.
